UNITED STATES PATENT OFFICE.

WILLIAM BROWN, OF WILMINGTON, DELAWARE.

PACKING-FRAME FOR SHIPPING PAPER.

SPECIFICATION forming part of Letters Patent No. 443,474, dated December 23, 1890.

Application filed March 8, 1890. Serial No. 343,083. (No model.)

To all whom it may concern:

Be it known that I, WILLIAM BROWN, of 5
Wilmington, in the county of New Castle and
State of Delaware, have invented an Improve-
ment in Packing-Frames for Shipping Paper,
of which the following is a specification.

My invention has reference to packing- 10
frames for shipping paper; and it consists of
certain improvements which are fully set
forth in the following specification and shown
in the accompanying drawings, which form a
part thereof.

In carrying out my invention I employ two 15
metallic frames substantially rectangular in
form and made of bars riveted together, so
as to expose preferably flat surfaces all in the
same plane, and these frames I place upon
20 the opposite sides of a package of paper and
bind the said frames to the paper by means
of cords.

The object of the frame is to prevent the 25
corners or edges of the paper package from
becoming damaged during shipment, and the
particular object in making the frames of
metal and of the construction hereinafter set
out is to require the least possible amount of 30
binding-cord, which becomes a waste product,
since it will never be returned. These frames
are for general use in shipment of paper by
35 the wholesale, and are returned to the ship-
ping-house as soon as the paper is delivered,
and are therefore used over and over again.

Referring to the drawings, Figure 1 is a 40
perspective view illustrating a package of
paper bound in my improved frames ready
for shipment. Fig. 2 is a cross-section of same
on line $\alpha\alpha$, and Fig. 3 is a perspective view
45 of one of the frames removed.

A represents the frames, which are formed 40
rectangular in shape, being made of two lon-
gitudinal bars B B, the end bars C C, and an
intermediate bar D, which are riveted to-
gether to form a rigid rectangular frame-
work. Where the bars lap, one of the lap- 45
ping-bars is bent, as at E, upon its ends, so
as to form a recess in which the other bar
meeting it at right angles rests, so that the
surfaces of the connecting-bars which come
adjacent to the paper are in the same plane.

As shown in Fig. 3, the ends of the longitudi- 50
nal bars B B are the ones which are bent at
E in the manner last described; but it is evi-
dent that, if desired, the bar C might be so
bent. The cross-bar D is formed with the
bends E upon its ends to receive the middle 55
of the bars B, as this makes the longitudinal
bars more strong than would be the case if
they were recessed or bent at their middle
portions to receive a straight bar D in place
of one having the bends E upon its ends. 60
The outer and upper edges of the bars B and
C are rounded, as indicated at b, so that the
wrapping-cords H and I in passing over the
edges of said frames shall not be cut or sev-
ered, which would result if the edges were 65
sharp or ragged.

G represents the paper and is inclosed in a
wrapper F, making a rectangular package. 70
(Very clearly shown in Fig. 1.) This pack-
age is placed upon an inverted frame A, and
a second frame A is placed upon its top, as
clearly indicated in the drawings. After this
is done the cords H' and I are tied over the 75
package and around the frame, making a
tight compact package having all of its up-
per and lower corners or edges bounded by
metal. The complete package is very clearly
shown in Fig. 1. It will be observed that by 80
the lapping of the bars B and C we will have
at the four corners of each surface of the
package a re-enforcing metallic protecting-
corner excellently adapted to resist the ex-
cessive strains which would be thrown upon 85
the package at these parts. Furthermore,
the raised portions H, formed by the lapping
of the several bars B, C, and D, act as feet
to support the package when laid upon the floor,
and thereby protect the cords from direct ex- 90
cessive abrasion, preventing the liability of
the package to become undone. Furthermore,
these projections H act as fulcrum-
points in tilting the package and prevent the
corners from cutting the cords.

I do not confine myself to the number of 95
cross-bars D, as more than one may be used,
if found necessary, in large packages. Neither
do I confine myself to the rectangular shape
of the frame.

Having now described my invention, what I claim as new, and desire to secure by Letters Patent, is—

A frame for packing paper and other articles, consisting of a series of bars having their body portions arranged in the same plane and united by being lap-jointed together, said lap-jointed portions forming small projecting

feet H upon one side of the frame, the other side having a flat even surface.

In testimony of which invention I have hereunto set my hand.

WILLIAM BROWN.
